UNITED STATES PATENT OFFICE.

CHARLES LEONARD PFEIFFER, OF BAYSIDE, NEW YORK, ASSIGNOR TO RICHARD HUENUT, OF NEW YORK, N. Y., A CORPORATION OF NEW YORK.

DESIGN FOR A BOTTLE OR SIMILAR CONTAINER.

Application filed February 21, 1928. Serial No. 25,528. Term of patent 14 years.

To all whom it may concern:

Be it known that I, CHARLES LEONARD PFEIFFER, a citizen of the United States of America, residing at Bayside, Long Island, in the county of Queens, State of New York, have invented a new, original, and ornamental Design for a Bottle or Similar Container, of which the following is a specification, reference being had to the accompanying drawing, forming part thereof.

Fig. 1 is a side view, and
Fig. 2 is a plan view showing my design.
I claim:

The ornamental design for a bottle or similar container as shown.

Dated at New York city, New York, this 23rd day of January, 1928.

C. LEONARD PFEIFFER.
